UNITED STATES PATENT OFFICE.

EARNEST NEWMAN, OF LAKE PROVIDENCE, LOUISIANA.

DECOY.

Application filed August 31, 1922. Serial No. 585,506.

To all whom it may concern:

Be it known that I, EARNEST NEWMAN, a citizen of the United States, residing at Lake Providence, in the parish of East Carroll 5 and State of Louisiana, have invented a new and useful Decoy, of which the following is a specification.

This invention relates to decoys to be used in gunning geese or the like, the primary 10 object of the invention being to provide a decoy goose of the collapsible type, wherein the device may be readily and easily stored when carried from place to place.

Another object of the invention is to provide 15 a device of this character wherein the sections may be securely locked together, to prevent displacement.

With the foregoing and other objects in view which will appear as the description 20 proceeds, the invention resides in the combination and arrangement of parts and in the details of construction hereinafter described and claimed, it being understood that changes in the precise embodiment of 25 the invention herein disclosed, may be made within the scope of what is claimed, without departing from the spirit of the invention.

Referring to the drawing:—

Figure 1 is an elevational view of a decoy 30 goose, constructed in accordance with the invention.

Figure 2 is a sectional view taken on line 2—2 of Figure 1.

Figure 3 is a fragmental detail view 35 showing one of the locking elements employed for locking sections of the decoys together.

Referring to the drawing in detail, the device embodies opposed sections 5 and 6, the sections being curved as clearly shown by 40 Figure 2 of the drawing, so that when the sections are brought together, the outline of the decoy will be that of a goose. These sections may be formed of any suitable material such as wood or stamped metal, the 45 body portion being suitably painted to simulate a wild goose.

The section 5 is formed with swinging latch members 7 disposed adjacent to one edge thereof, so that when the latch members

are moved to their latching positions, the 50 same will overlie the line of connection between the sections to brace the sections.

The latch members are formed with openings 8 extending from one of the side edges thereof, so that the same may be moved into 55 engagement with the pins 9, carried by the opposed section, the pins being formed with heads to contact with the latch members and prevent movement of the latch members. Bolts 10 extend through the sections 5 and 60 6 adjacent to the lower side edges thereof, which bolts are designed to pass through suitable openings formed in the supporting band 11 to accommodate the winged nuts 12 whereby the supporting band may be secured 65 to the body portion of the decoy.

Disposed intermediate the ends of the band 11 is a depending rod 13 which has its lower end tapered as at 14 to pierce the ground surface to enable the user to properly 70 position the decoy.

From the foregoing it will be seen that I have provided simple and efficient means for securing the sections together, and at the same time provided novel means whereby the 75 sections may be disconnected to permit them to be readily stored for transportation.

What is claimed as new is:—

A decoy comprising opposed sections, the sections being constructed to simulate a 80 goose, when the sections are brought together, latching members at the upper portion of the sections for securing the sections together, bolts disposed adjacent to the lower portion of the sections, a band having openings, said band adapted to engage the under-surfaces of the sections, the openings adapted to receive the bolts to secure the sections together, and a rod having connection with the band to provide a support for 85 90 the decoy.

In testimony that I claim the foregoing as my own, I have hereto affixed my signature in the presence of two witnesses.

EARNEST NEWMAN.

Witnesses:

J. M. WILLIAMS.
